O. FITZSIMMONS.
BOTTLE CARRIER AND SUPPORT.
APPLICATION FILED OCT. 2, 1920.

1,391,537.

Patented Sept. 20, 1921.

INVENTOR.

Osborne Fitzsimmons,

BY

Geo. Kimmel.

ATTORNEY.

UNITED STATES PATENT OFFICE.

OSBORNE FITZSIMMONS, OF CHICAGO, ILLINOIS.

BOTTLE CARRIER AND SUPPORT.

1,391,537.

Specification of Letters Patent. Patented Sept. 20, 1921.

Application filed October 2, 1920. Serial No. 414,184.

To all whom it may concern:

Be it known that I, OSBORNE FITZSIMMONS, a citizen of the United States, residing at Chicago, in the county of Cook and 5 State of Illinois, have invented certain new and useful Improvements in a Bottle Carrier and Support, of which the following is a specification.

This invention relates to a bottle carrying 10 and supporting device of the type engageable with a bottle neck.

The object of the invention is to provide a simple and efficient device of this character embracing a minimum number of parts having 15 a maximum efficiency.

Another object is to provide a device of this character composed of superposed split rings connected to slide one on the other and to expand and contract, said rings having 20 handle engaging arms and equipped with means to hold said arms diametrically opposite at all times.

With these and other objects in view, the invention consists in certain novel features 25 of construction as hereinafter shown and described, and then specifically pointed out in the claims, and in the drawings illustrative of the preferred embodiment of the invention.

30 In the accompanying drawing:

Figure 1 represents a side elevation of the device constituting this invention.

Fig. 2 is a bottom plan view thereof with the arms in section;

35 Fig. 3 is a transverse sectional view, on line 3—3 of Fig. 1, and,

Fig. 4 is a detail sectional view.

The embodiment of the invention herein 40 illustrated comprises two superposed split rings 1 and 2 preferably constructed of heavy spring wire and provided at one end with laterally extending arms 3 and 4, the arm of one ring being arranged and held diametrically opposite the other at all times

45 by means presently to be described. These arms 3 and 4 have their terminals arranged at right angles and equipped with eyes 15 for engagement by similar members carried by a bail shaped handle 16.

50 The split ring 1 has a band 5 fixed thereto adjacent the base of its arm 4 and said band carries a sleeve 6 in which ring 2 is mounted to slide. The other end of the ring 1 has a band 7 fixed thereto with a sleeve 8 carried 55 thereby in which sleeve ring 2 slides.

The other split ring 2 has secured at its opposite ends similar bands 8 and 10, respectively, each carrying a sleeve 9 and 11 in which ring 1 is mounted to slide. Two lugs 12 and 13 are carried, one by the ring 60 2 and the other by ring 1 and are positioned at diametrically opposite points, the lug on one ring being positioned between the ends of the other ring so that the bail carrying arms 3 and 4 are at all times held diametrically opposite each other.

By so constructing this bottle carrier and providing the lugs 12 and 13 the rings 1 and 2 may be expanded and contracted and moved one on the other to adapt the device 70 to be applied and removed with ease from a bottle neck and which when in operative position will firmly grip the bottle neck and hold the carrier securely engaged therewith.

The expansion and contraction of the 75 respective rings is accomplished by grasping the arms 3 and 4 and moving them toward each other in one direction or the other and the lugs 12 and 13 operate to hold said arms diametrically opposite at all times.

The preferred embodiment of the invention is disclosed in the drawings and set forth in the specification, but it will be understood that any modifications within the 80 scope of the claims may be made in the construction without departing from the principle of the invention or sacrificing any of its advantages.

What is claimed is:

1. In a device of the class described, a 90 split ring having a laterally extending arm at one end, a coöperating similarly shaped ring having its arm located diametrically opposite the first mentioned arm, a pair of spaced sleeves fixed to each of said rings 95 one ring being slidably mounted in the sleeves of the other ring, and means whereby said arms are retained always at diametrically opposite points.

2. In a device of the class described, a 100 split ring having a laterally extending arm at one end, a coöperating similarly shaped ring having its arm located diametrically opposite the first mentioned arm, a pair of spaced sleeves fixed to each of said rings 105 one ring being slidably mounted in the sleeves of the other ring, lugs carried one by one ring and one by the other, the lug carried by one ring being positioned between the ends of the other ring whereby said arms 110

are retained always at diametrically opposite points.

3. In a device of the class described, a split ring having a laterally extending arm 5 at one end, a coöperating similarly shaped ring having its arm located diametrically opposite the first mentioned arm, a pair of

sleeves fixed to each of said rings at opposite ends thereof, one ring being mounted to slide in the sleeves of the other.

In testimony whereof I affix my signature hereto.

OSBORNE FITZSIMMONS.
